UNITED STATES PATENT OFFICE.

HUBERT C. SHARP, OF SANTA PAULA, CALIFORNIA, ASSIGNOR TO CALIFORNIA WALNUT GROWERS ASSOCIATION, OF LOS ANGELES, CALIFORNIA, A CORPORATION OF CALIFORNIA.

WALNUT-BRANDING MACHINE.

Application filed January 27, 1926. Serial No. 84,021.

This invention relates to branding machines and relates more particularly to machines for imprinting marks on articles of irregular surface contour and to means for segregating such articles so that the machine will operate continuously and will imprint the mark on each article conducted through the machine.

Many attempts have heretofore been made to brand or imprint marks or indicia on walnuts which are of irregular size as well as irregular exterior contour. The principal difficulty which has been encountered is the segregating of the walnuts so that they will be conveyed past a printing or stamping member in single continuous file so that each walnut will be stamped or marked by the printing or branding element irrespective of the position upon the conveying member which the walnut takes, that is, whether the same is positioned upon one end so that the opposite end thereof is presented to the inking or branding member or whether the walnut rests on its side on the conveyor member and presents the opposite side thereof to the printing or branding member. In attempting to segregate walnuts into a single file so that a continuous stream of walnuts is fed past a printing member great difficulty has been encountered in the arching of the walnuts on the preliminary delivery means so that the travel or delivery of the walnuts to the branding element is arrested.

It is therefore an object of this invention to provide a machine for branding or imprinting indicia or marks on walnuts or other articles of irregular surface contour and of irregular size in which means are provided for segregating the walnuts into single file streams and delivering these single file streams to a conveyor or by means of which the same are conveyed into position to be marked or branded.

Another object of this invention is to provide a machine for branding or imprinting marks upon walnuts in which means are provided for segregating a mass of walnuts from a receiving hopper into a single layer thereof so that arching of the walnuts is prevented and which walnuts are delivered in single file streams through a plurality of independent printing or branding units.

Another object of this invention is to pro-

vide an improved form of printing or marking types or dies for printing or branding indicia upon the surfaces of walnuts and the like.

Other objects and advantages of this invention will be apparent from the following detailed description of a preferred embodiment thereof as illustrated in the accompanying drawings, in which drawings:

Figure 1 is a side elevation of a walnut branding and packing apparatus embodying this invention.

Figure 2 is an enlarged side elevation partly in section of a walnut branding machine embodying this invention.

Figure 3 is a top plan view thereof illustrating a walnut branding machine embodying this invention and illustrating the inking mechanism and imprinting dies as moved and illustrating a portion of the top plate covering the individual delivery troughs as broken away.

Figure 4 is an enlarged fragmental side elevation of an inking transfer mechanism embodied in this invention for transferring ink to the branding or printing dies or

Figure 5 is a top plan view taken substantially on the line 5—5 of Figure 4.

Figure 6 is an enlarged fragmental view of mechanism employed for oscillating the ink transfer roller.

Figure 7 is a perspective view of a unit band for carrying the dies or stamps for imprinting marks upon the walnuts.

In the preferred embodiment of this invention illustrated in the accompanying drawings, 1 illustrates a conveyor which is mounted within a trough 2 upon which conveyor the articles, such as walnuts, to be marked or branded are conveyed to a vertically extending discharge chute 3, which chute 3 is positioned so that the walnuts fall directly upon a separating plate 4, mounted within the oscillating frame 5 of the walnut branding machine.

The oscillatory frame 5 is supported at the shaft 6 at one end and at the hardened steel plates 7 at its opposite end. The shaft 6 is rigidly secured within the bosses 7a which are formed at the end of the arms 8 and which arms 8 are formed integral with the oscillatory frame 5. The rocker arm 9 is

secured to the shaft 10, which shaft 10 is likewise secured to the crank lever 11, which crank lever 11 is secured at the pin 12 in the slot 13 to the connecting rod 14, which connecting rod 14 is secured to the eccentric sheave 15 mounted on the counter-shaft 16. Formed integral with the eccentric sheave 15 is a pulley 17, which pulley 17 is driven by means of a belt 18 from a motor 19. By means of this drive, it will be noted that the entire frame 5 is given an oscillatory motion substantially in a horizontal plane so that the receiving plate 4 is oscillated to and fro in this horizontal plane.

10 The receiving plate 4 is pivotally supported within the oscillatory frame 5 at a pin 20 and is adjustably secured to the frame 5 at its opposite end at a pin 21 which is mounted within a slot 22 formed in the side 20 member of the frame 5 so that the incline from the horizontal of the receiving plate 4 may be adjusted. The walnuts to be branded leaving the receiving plate 4 fall upon a second receiving plate 23 which is 25 likewise supported within the oscillatory frame 5 at a pin 22^a at one end and at an arcuate slide 24 at the opposite end, which slide 24 is adjusted in position at a set-screw 25, so that the position or inclination of the 30 plate 23 may be adjusted. A third receiving plate 26 is also mounted within the oscillatory frame 5 at a pin 27 at one end and at an arcuate slide 28 at the opposite end, and is adjustable in position on the slide 28 at a 35 set-screw 29. Mouted on the plate 26 are frames 26^a, which frames 26^a divide the plate 26 into a plurality of guide troughs 26^b.

The hardened plates 7 at the forward end of the oscillatory frame 5 ride upon rollers 40 30 mounted within a bracket 31.

The walnuts leaving the guide troughs 26^b are discharged in single file into the troughs 35 formed on the plate 36 by the partitions 37, the troughs 35 being so spaced as to 45 permit the walnuts to travel therethrough in single file and the base-plate 36 being inclined so that the walnuts will travel through the troughs 35 due to the inclination thereof and the oscillatory motion imparted to the oscillatory frame 5 to which and within which the base 36 is secured and supported.

Formed integral with the bracket 31 which supports the roller 30 is a casting 38 55 which provides a base 39 which is curved at its upper face 40 and which provides a plurality of separate troughs 41. The walnuts travel by gravity over the curved face 40 and drop into pockets 42 of the individual rollers 43 which are mounted in position adjacent the discharge end of each separate trough 41. The cups 42 formed in these individual rollers or wheels 43 are preferably of the form of a segment of a sphere. The individual rollers 43 are keyed 60 to the shaft 44, which shaft 44 is keyed to the sprocket 46 over which sprocket 46 a chain 47 is trained and which chain 47 passes over the idler sprocket 48 on the shaft 49 and is driven by a sprocket 50 keyed to the shaft 51, which shaft 51 is driven through gears 52 from the counter-shaft 16.

The rollers 30 are mounted on pins 53, which pins 53 are secured within the brackets 31 at the ends to rocker-arms 54, which rocker-arms 54 are pivotally supported on shaft 49 so that the elevation of the frame 5 may be regulated at the exit end.

A plurality of wheels 56 carrying bands 57 to which stamps 58 are secured are keyed to a shaft 59 there being one wheel 56 for each wheel 43. The stamps 58 are supported over recesses 60 formed in the periphery of the wheel 56 and the band 57 is formed of a flexible material such as rubber or the like. 85 The shaft 59 is driven from the shaft 44 through gears 61.

The stamps 58 are supported in position upon the individual wheel 56 in position so that the same engage the walnuts within the 90 cups 42 formed in the periphery of the wheel 43. Means are provided for inking the stamps 58, which means are preferably of the following construction:

An ink cup 62, in which semi-fluid ink is 95 placed, is rotatably supported at a pin 63 mounted in a plate 64, which plate 64 fits within a frame 65 and is pivoted therein at the end 66 of the plate 64. The frame 65 is pivotally supported at a pin 67 to the frame 100 of the apparatus at one end and is pivotally supported at a pin 68 to link 69 at its opposite end, which link 69 is secured to a link 70 adjustably secured to the frame of the apparatus at 71. A hand-screw 72 is screw-threaded into the plate 64 which abuts the frame 65 at its lower end so as to adjustably support the plate 64 within the frame 65 so that the angle of inclination of the ink cup 62 may be regulated thereby. The chain 47 110 is trained over a sprocket 73 which is keyed to a shaft 74, which shaft 74 is journaled in bearings supported by the frame of the apparatus. Transfer units 75 are secured to the shaft 74 in spaced relation and comprise 115 a hub 76 which is adjustably secured to the shaft 74 at a set-screw 77 and have transfer paddles 78 pivotally secured thereto at pin 79 so that when the shaft 74 is rotated the transfer paddles 78 are rotated into the ink cup 62 and receive ink on their lower ends. The abutting or transfer paddle 78 with the ink cup rotates the ink cup 62 on the pin 63. The paddles 78 carry the ink to an upper ink roller 80, which ink roller 80 transfers ink 120 through a pair of idle rollers 81 and 82 to the ink delivering roller 83, which ink delivering roller 83 transfers the ink to a transfer roller 84 which is pivotally supported at a pin 85 by the arms 86, which 125

arms 86 are loose on the shaft 87 which is mounted in bearings supported by the frame of the apparatus. The shaft 87 is reciprocated transversely of the apparatus so as to transversely move the transfer rollers 84 across the roller 83 so as to obtain a uniform distribution of ink from the periphery of the roller 84 by means of a fork 88 which is pivotally supported on the shaft 87 and which fork 88 forms one branch of a lever 89 which is secured to a shaft 90 at an eccentric bearing 91 so that the lever 89 is given a reciprocatory motion. The shaft 90 is driven to worm-gears 92 from the shaft 15 44.

The walnuts having been separated into single file streams by the combined horizontal reciprocatory motion of the frame 5 and the vertical oscillation thereof pass into the 20 cups 42 of the wheels 43. The wheel 43 carries the nuts past the stamps 58 by means of which the brand or mark is imprinted on their surface and the nuts are then delivered into a discharge chute 93 and into a hopper 25 94 where they are directed into a bag 95 supported at the discharge or hopper 94. In this manner, the walnuts are sacked and are ready to be delivered to the customer. The entire apparatus is supported by a 30 frame 96 which is mounted upon wheels 97 so that the same may be moved if desired.

The stamps 58 which are mounted upon the bands 57 comprise a block 98 of resilient material, such as a sponge rubber, which is 35 cut away at a V-shaped slot 99 at the sides. The branding stamp 100 is secured to the upper face of these blocks 98. The stamp 100 being so supported may easily conform to the curved contour irrespective of the 40 irregularity of the walnuts to be stamped, the sponge roller 98 permitting the easy compression or retardation of the stamps 100 so that a clear and even imprint is made upon the surface of the walnut irrespective of whether the stamp abuts one of the 45 smaller ends of the walnut or whether the same prints upon one of the comparatively flat surfaces of the walnut.

Having fully described a preferred embodiment of this invention, it is to be understood that I do not wish to be limited to the terms of the construction herein set forth which may obviously be varied without departing from the spirit of my invention as 50 set forth in the appended claims.

I claim:

1. In a branding machine, the combination of an oscillatory frame, a plurality of receiving plates adjustably mounted within the frame, means for oscillating the frame, and marking means adjacent the delivery 55 end of the oscillatory frame.

2. In a branding machine, the combination of a delivery frame, means for delivering 60 articles to be branded to the said frame,

means for imparting a stepwise reciprocatory and advancing motion to the articles within the frame, means for segregating the articles into single file streams, and means for marking the articles so segregated. 70

3. In a branding machine, the combination of a delivery frame, means for delivering articles to be branded to the said frame, a plurality of receiving plates adjustably mounted within the frame and means for imparting a reciprocatory motion to the receiving plates, means for segregating the articles in single file streams, and means for marking the articles so segregated. 75

4. In a branding machine, the combination of a delivery frame, means for delivering articles to be branded to the said frame, a plurality of receiving plates mounted within the frame, means for imparting a reciprocatory motion to the receiving plates, a plurality of partitions on the latter of said receiving plates for segregating the articles into single file streams, means for conveying the articles so segregated from the latter said receiving plate to a conveyor, and means 85 mounted adjacent the conveyor for marking the articles. 90

5. In a branding machine, the combination of a delivery frame, means for delivering articles to be branded to the said frame, a plurality of receiving plates adjustably mounted within the frame, means for imparting horizontal reciprocatory motion to the said receiving plates, means for segregating the articles into single file streams, and means 95 for marking the articles so segregated. 100

6. In a branding machine, the combination of an oscillatory frame, a plurality of receiving plates mounted within the frame, means for imparting an oscillatory motion to the said frame, means for delivering articles to be marked to the said receiving plates, means for segregating the articles into single file streams, a plurality of wheels having cupped peripheral recesses formed 105 therein, means for conveying articles in single file streams from the receiving plates to the cups formed in the said wheels, a plurality of printing wheels having peripheral recesses, printing stamps mounted over the 110 said recesses, and means for rotating the said cupped wheels and the said printing wheels in co-operative relation so that the said peripheral recesses and cups are maintained in alignment. 115

7. In a branding machine, the combination of an oscillatory frame, a plurality of receiving plates adjustably mounted within the frame, means for imparting a substantially horizontal reciprocatory motion to the said frame, means for segregating the articles into single file streams, a plurality of unit marking means for marking the articles so segregated, each of which units comprises 125 a cupped conveyor wheel, a printing wheel 130

having peripheral recesses formed therein, stamps spanning the recesses, and means for applying ink to the said stamps.

8. The combination with a branding machine of a printing wheel having a plurality of peripheral recesses formed therein, stamps spanning the recesses, each of which stamps comprises a block of resilient material having a V-shaped slot in its sides, and a branding stamp secured to the surface of said block.

9. In a walnut branding machine, the combination of an enclosed conveyor, a chute into which the conveyor delivers the articles to be branded, an oscillatory frame mounted in position with one end adjacent the said chute to receive the said articles, means for imparting a stepwise reciprocatory and advancing motion to the articles within the said frame, means for segregating the articles into single file streams, and means for marking the articles so segregated.

10. In a branding machine, the combination of an oscillatory frame, a plurality of independent receiving plates pivotally supported at one end within the frame and adjustably supported at their opposite ends

within the frame so as to permit adjustment of their inclination means for reciprocating the said oscillatory frame, means for segregating the articles into single file streams, and means for marking the articles so segregated.

11. In a branding machine, the combination of a frame, means for pivotally supporting the frame at one end, means for slidably supporting the frame at its opposite end, means secured to the pivot end of the said frame for imparting a substantially horizontal oscillatory motion to the said frame, a plurality of inclined receiving plates mounted in the said frame so as to permit adjustment of the inclination thereof, a partitioned segregating plate mounted within the said frame so as to be reciprocated therewith, delivery troughs communicating with the said segregating plate and conveying the articles to be marked in single file, and means adjacent the delivery end of the said trough for marking the articles so segregated.

Signed at Los Angeles, Calif., this 20th day of January, 1926.

HUBERT C. SHARP.
